UNITED STATES PATENT OFFICE.

WALTER SCOTT HAMILTON AND JAMES ROZIER WILLIAMS, OF HOUSTON, TEXAS.

WASHING-MACHINE.

No. 889,924.

Specification of Letters Patent.

Patented June 9, 1908.

Application filed June 22, 1907. Serial No. 380,329.

To all whom it may concern:

Be it known that we, WALTER SCOTT HAMILTON and JAMES ROZIER WILLIAMS, citizens of the United States, residing at Houston, in the county of Harris and State of Texas, have invented a new and useful Washing-Machine, of which the following is a specification.

This invention relates to a washing machine of the type wherein a basket for holding clothes to be washed is inclosed within a suitable tub or other vessel containing hot soapy water, and by some suitable means, either manual or power, the basket is given an oscillatory movement in both a horizontal and vertical direction.

The object of the invention is to provide a simple, quick and efficient machine for washing clothes with great ease and without damage to the most delicate fabrics, by moving the clothes held in a perforated carrier through hot soapy water which latter is forced by the movement of the carrier through the interstices of the clothes and rapidly removes the dirt therefrom.

In the accompanying drawings: Figure 1 is a vertical central sectional view of the improved washing machine. Fig. 2 is a horizontal sectional view of the same on the line 2—2 with the cover removed. Fig. 3 is a top plan view.

Similar reference numerals are used to designate the same parts on all the figures.

Within a tub or other suitable receptacle 1 is a basket 2 for containing clothes to be washed, supported on an undulating track 3, fastened to the inside of the tub or receptacle, and caused to travel thereover when a horizontal lever 4 is oscillated.

The receptacle 1 may be made of metal or wood, preferably the former, cylindrical in shape and closed at the top by a flanged cover 5 having a central perforation 6 and two diametrically disposed curved slots 7 each having at its center a radial notch 8. The undulating track 3 is supported near the top of the receptacle 1 on brackets 9 projecting a short distance from the sides of said receptacle. In plan, the track appears circular, but in elevation it will be seen to consist of a series of elevations 10 and depressions 11 extending entirely around the receptacle. The number of undulations may be varied, but the track shown in the drawings has three elevations and three depressions.

Above each depressed portion 11 of the track

is a guard rail 12 lying parallel with the track and reaching nearly to the summit of the elevation 10 on either side.

The basket 2 comprises a suitably constructed frame lined with woven wire netting of coarse mesh to form a flat bottomed cylindrically shaped clothes holder. The basket 2 is suspended from the track 3 by hangers 13, fastened to the rim 14 of the basket, on each of which hangers a flanged wheel or roller 15 that runs on the track, is journaled. Three such rollers 15 equally spaced, are shown in the drawing, but the number may be varied if desired. The rollers or wheels 15 rest normally in the depressed portions of the track and are covered by the guard rails 12 which prevent the rollers from becoming derailed as the basket is operated.

Extending upwardly from the basket 2 through the curved slots 7 in the cover 5 are two arms 16 and 17 connected to the hand lever 4. The arm 16 has its upper end formed into a hook 18 to engage an eye 19 on one end of the hand lever 4. The other arm 17 is flattened and enters a slot 20 in the hand lever and is temporarily fastened thereto by a removable pin 21. The hand lever 4 overhangs the cover and carries a knob 22 on its outer end to be grasped by the hand.

Within the basket 2 is a perforated plate or disk 23 fastened at its center to the lower end of a rod 24 and, passing through the center hole 6 in the cover and a hole in the hand lever 4, is adjustably secured to the lever by a thumb nut 25. After the clothes to be washed have been placed in the basket, the plate or disk 23 is lowered over them and holds them in place during the washing process.

To use this machine, the pin 21 is withdrawn from the hand lever 4 and the thumb nut 25 loosened so that the hand lever may be thrown back as indicated by dotted lines in Fig. 1. The cover is then removed and the disk 23 withdrawn from the basket. A suitable quantity of suds water must now be placed in the receptacle and the dirty clothes in the basket. The disk, cover and handle are now replaced, the knob 22 grasped by the hand and moved to and fro in a horizontal direction. This will cause the basket of clothes to swing on its axis and also to rise and fall as the rollers or wheels 15 travel up and down the undulating track.

The sudden changes in the direction of movement of the receptacle forces the water

through the clothes and the meshes of the fabric and so thoroughly and quickly cleanses them.

The basket may be removed from the receptacle by turning it so that the wheels or rollers will ride up on the highest points of the elevations 10 over which the guard rails do not extend.

Having thus described the invention what is claimed is:—

1. A washing machine comprising a receptacle, a revoluble clothes holder therein, an undulating track within the receptacle, means carried by the holder and movable upon the track for supporting the holder within the receptacle, and guard rails above and concentric with the depressed portions of the track for positively directing the holder downward during the rotation thereof.

2. A washing machine comprising a receptacle or tub, a perforated clothes holder or basket suspended within said tub, means for oscillating said basket about a vertical axis, an undulating track within said receptacle and attached to its walls, spaced rollers on said basket mounted on said track and adapted to raise and lower said basket as it is oscillated, and an adjustable disk for holding the clothes in the basket.

In testimony that we claim the foregoing as our own, we have hereto affixed our signatures in the presence of two witnesses:

WALTER SCOTT HAMILTON.
JAMES ROZIER WILLIAMS.

Witnesses:

MOSES PARISH POLLARD,
EDWARD ERISMAN HOFFMANN.
